(57) **CLAIM**

The ornamental design for a building panel, as shown and described.

DESCRIPTION

FIG. 1 is a front, top perspective view of a first embodiment of a building panel;

FIG. 2 is a rear, top perspective view thereof;

FIG. 3 is a front, bottom perspective view thereof;

FIG. 4 is a rear, bottom perspective view thereof;

FIG. 5 is a front elevation view thereof;

FIG. 6 is a rear elevation view thereof;

FIG. 7 is a left-side elevation view thereof;

FIG. 8 is a right-side elevation view thereof;

FIG. 9 is a top plan view thereof; and,

FIG. 10 is a bottom plan view thereof.

The broken lines are for the purpose of illustrating portions of the article that form no part of the claimed design. The hand logo shown in dash-dot broken lines is a trademark owned by FIVES DESIGNS, LLC (Boise, ID). The hand logo forms no part of the claimed design.

1 Claim, 4 Drawing Sheets
